UNITED STATES PATENT OFFICE

2,179,133

NECKTIE

Frank Charles Rehor, New York, N. Y.

Application May 19, 1936, Serial No. 80,491

3 Claims. (Cl. 2—146)

This invention relates to neckties. More particularly, it relates to neckties of the four-in-hand type and to a method of making the same.

One of the objects of my invention is to provide a necktie of the character described in which the folded over portions on the back of the tie are so disposed as to eliminate the raised longitudinal ridge usually found in such neckties.

Another object of my invention is to provide a necktie of the character described in which the size and contour of the lining fabric is in such relationship to the size and contour of the tie fabric that the tie will maintain its shape at all times.

Still another object of my invention is to provide a necktie of the character described, as well as a method of making the same, which shall be relatively inexpensive to manufacture, which shall be resiliently constructed so as to hold its shape under all conditions of use, and which shall be strong and at the same time neat in appearance.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

Certain features described but not claimed in this application are described and claimed in my co-pending application, Serial No. 80,490 filed simultaneously herewith.

Fig. 1 is a plan view illustrating the contour of the tie fabric, embodying certain features of my invention;

Fig. 2 is a plan view of the fabric with lining superimposed thereon, and illustrating a step in my improved method of necktie making;

Fig. 3 is a view similar to Fig. 2, but illustrating another step in my improved method;

Fig. 4 is a plan view of the back of the completed tie, embodying the various features of my invention;

Fig. 5 is a sectional view taken substantially on the line 5—5 of Fig. 3; and

Fig. 6 is a sectional view taken substantially on the line 6—6 of Fig. 5.

Referring now in detail to the drawing, I have disclosed in Fig. 1 a tie fabric 10, which may be cut from a specially designed stencil or pattern, and comprising a suitable length of material having longitudinal edges 11 of the usual tie contour, and ends 12 and 13 which are provided with a plurality of points *a*, *b* and *c*, and indentations

x and *y*. The purpose and function of the specially designed fabric ends 12 and 13 will become apparent as the description proceeds.

Superimposed on the tie fabric 10, is a lining fabric 15, which may be coextensive in length with the fabric 10, but of narrower width. The lining 15 is centrally disposed with respect to the fabric 10, and is provided with pointed ends adapted to coincide with the points *b* of the fabric 10. It is noted that the edges 16 of the lining 15 are substantially parallel to the edges 11 of the fabric 10, and that the contour and size of the lining 15 is substantially the contour and size of the finished necktie, as illustrated in Fig. 4.

After the lining 15 has been properly positioned as described above, the tie fabric edges 11 are

folded over on the longitudinal axes *x*—*x* and *y*—*y*. It will be noted that the end edge portions *a*—*x* and *c*—*y* of the tie fabric 10, when in folded position as shown in Fig. 3, will be sub-

stantially parallel to the end edge portions *x*—*b* and *y*—*b* respectively, and that the longitudinal edges 11 of the tie fabric, when folded over in the above described manner, will be contiguously disposed in relation to the longitudinal edges 16 of the lining 15. The lining edges 16 and the folded fabric edges 11 are then sewed together in any suitable manner employed for stitching tie fabrics together, well known in the art. One such method may comprise the folding over of the raw edges 11 of the tie fabric 10 and sewing the said folded edges to the folded lining edges 16, as illustrated in Fig. 5. If desired, the end edge portions *a*—*x* and *y*—*c* of the fabric 10 may be so designed that, when in their folded position, *a*—*x* and *y*—*c*', as shown in Fig. 3, said end edge portions will be slightly spaced inwardly from the edges *x*—*b* and *y*—*b*. This is done to facilitate the next step in my improved method of man-

ufacture, which comprises turning in the raw edges of the ends *x*—*b* and *y*—*b* of the tie fabric 10 and sewing them to the end edges of the lining 15 and to the folded end portions *a*—*x* and *y*—*c*' of the fabric 10. (See Fig. 3.)

The longitudinally folded tie fabric edges *x*—*x* and *y*—*y* are now again folded inwardly toward each other on the longitudinal axes *a*'—*a*' and *c*'—*c*', so that the said longitudinal edges *x*—*x* and *y*—*y* will be substantially contiguously dis-

posed in the center of the back of the necktie, as clearly illustrated in Figs. 4 and 6.

By this construction and method of manu-

facture, I have been able to provide a necktie of the character described in which there is eliminated the raised longitudinal ridge on the back

50
55
55

thereof, usually caused by overlapping ends of the folded over fabric.

To retain the edges $x-x$ and $y-y$ in contiguous relationship as above described, they may be joined by a plurality of interconnecting bar stitches 20, or any other suitable stitching or fastening means may be employed.

While in the drawing I have illustrated a necktie of the four-in-hand type in which two fabrics are employed, it is understood that my invention is adapted for use in connection with any other type of necktie, and in neckties composed of a different number of fabrics.

Also, it is understood that the tie fabric and lining fabric illustrated in the drawing may be cut on the bias, in the manner well known in the trade, in order to impart a certain amount of resilience to the finished necktie. Also, the stitches employed for sewing the fabrics together may be of the type known as merrow stitches, or any other type of resilient stitch.

It will thus be seen that there is provided a method and apparatus in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim

as new and desire to secure by Letters Patent:

1. As an article of manufacture, a necktie of the character described comprising a folded tie fabric and a non-folded lining, said lining being substantially equal in size and contour to the size and contour of the completed tie, and having its opposed longitudinal edges secured to the opposed longitudinal edges of the tie fabric throughout to form a continuous-wall hollow casing.

2. As an article of manufacture, a necktie of the character described comprising a folded tie fabric having four longitudinal folds and a non-folded lining, said lining being substantially equal in size and contour to the size and contour of the completed tie, said lining being secured to the opposed longitudinal non-folded edges of the fabric throughout its entire length.

3. A necktie of the character described comprising a tie fabric having end edges with correspondingly indented points and longitudinal side edges and a lining substantially equal in length to said fabric but of lesser width throughout, and having end edges which are coextensive with only a portion of the fabric end edges, said opposed side edges of the fabric being secured to opposed side edges of the lining, each of the opposed side edges of the fabric being folded toward each other upon two longitudinal fold lines, one of said fold lines being formed by the corresponding indented points at opposite ends of the fabric and the other of said fold lines coinciding with the side edges of the lining.

FRANK CHARLES REHOR.
